WATER SHUT-OFF FOR OIL WELLS

Charles A. Brown, Beaverton, Mich.

Application February 1, 1937, Serial No. 123,393

7 Claims. (Cl. 166—14)

This invention relates to shut-offs, and more especially to means for capping the upper end of the outer drive casing to tightly close the space between the inner and outer casings.

One of the prime objects of the invention is to prevent the overflow of water from the space between the inner casing and the outer drive casing to prevent pollution of surrounding land, and the killing of vegetation in the area polluted by this overflow.

Another object of the invention is to provide a simple, practical, and substantial means which can be readily assembled and applied in the field, without welding, or without the use of other spark producing equipment, which is dangerous to life and property when working on oil fields.

A further object is to design a shut-off which is economical to manufacture, which can be easily handled, and which can be applied by unskilled labor and with few tools.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit or sacrificing any of the advantages of the invention.

In the drawings—

Fig. 1 is a view of an oil well showing my shut-off in position thereon.

Fig. 2 is an enlarged fragmentary side elevational detail view of the shut-off.

Fig. 3 is a top plan view thereof.

Fig. 4 is an enlarged fragmentary sectional side elevational view taken on the line 4—4 of Fig. 2.

Fig. 5 is an enlarged fragmentary sectional view showing an alternate construction for use when the inner casing is run.

Fig. 6 is a top plan view thereof.

Fig. 7 is a sectional view similar to Fig. 2 and showing a removable top plate.

Fig. 8 is a top plan view thereof.

Fig. 9 is a detail plan view of the removable top plate.

Fig. 10 is an edge view thereof taken on the line 10—10 of Fig. 9.

Referring now more specifically to Figs. 2, 3, and 4 in which I have shown one embodiment of my invention, the numeral 9 indicates the outer drive casing, such as used when drilling an oil well, said casing being formed of a plurality of lengths of pipe suitably threaded at the ends and

secured together by means of couplings 10 as usual to form a continuous conduit or casing.

This outer casing is usually sunk to a depth until it rests on solid rock and the inner casing 11 is then run, and this is also formed of a plurality of pipe sections secured together by couplings 12 as usual, the upper ends of these inner and outer casings extending a short distance above the ground when the well is completed, or may be located in a pit if desired.

In most locations the oil bearing strata is relatively deep and when the outer drive casing is sunk and the inner casing is run, water flows from the space between the two casings, this water is salty, has a mineral content, and often contains a slight mixture of crude petroleum, all of which is injurious to vegetables and water life, and as it flows from the casing it overflows the surrounding territory, killing all vegetation and rendering the land unfit for productive agricultural purposes, the water finally finding its way to streams or rivers, polluting the water and killing fish, etc., and I have, therefore, provided a shut-off for capping this space between the inner and outer casings, without interfering with the natural flow or the pumping of oil from the inner casing.

The shut-off proper is preferably cylindrical in shape, being split on the center line 13 to divide it into a pair of identically similar sections 14 and 15 respectively, which when in assembled relation closely fit the outer casing, all as clearly shown in Figs. 2, 3, and 4 of the drawings, the upper end 16 being closed as shown, and is provided with a centrally disposed opening 17 to accommodate the coupling 12, which serves to secure the pipe sections of the inner casing together.

Diametrically opposed offset chambers 18 and 19 are provided in the sections 14 and 15, and wings 20 are provided on each section as shown, said wings being spaced from the abutting edges of the respective sections and are provided with openings 21 which accommodate bolts 22 for rigidly securing the sections together and clamping them in position on the outer drive casing.

Casing clamps 23 are provided on the inner casing as shown, and are secured together by means of the bolts 24, and the lower edge of the pipe coupling 12 resting on the upper edges of said clamps and supporting the inner casing, the projecting ends of the clamps extending into and being accommodated in the chambers 18 and 19 provided in the sections 14 and 15, thus the

inner casing rests on and is centrally held with relation to the outer drive casing.

In applying my shut-off to an oil well which has been, or is in operation, the sections 14 and 15 are first placed in assembled relation, (the clamps 23 being already in position) the bolts 22 are tightened to clamp the sections on the casing, thus providing a water-tight connection and structure which effectively seals the upper end 10 of the outer casing against overflow of water, etc. Paint or suitable sealing compound can, of course, be used on the contacting surfaces if desired and likewise gaskets may be used at certain points without departing from the spirit 15 of the invention.

In Figs. 5 and 6 of the drawings I have shown an alternate construction which I prefer to use when the well is being drilled, and when the inner casing is run. This consists of a pair of 20 spaced apart packing discs 25 and 26 respectively, said discs being formed in sections, each disc being hinged as at 27 to facilitate the assembly, and assembling lugs 28 also are provided on each disc.

25 In practice one disc is placed in the coupling 10 and rests on the upper end of one of the pipe sections which form the outer drive casing, a suitable packing 31 is then placed on this disc, after which the disc 26 is placed on the packing, 30 segment blocks 32 are then placed on the disc 26, the inner casing is then strained up and the clamps 23 placed in position, and when the casing is released the clamps bear on the segment blocks, pressing and wedging the packing material 30 so that a tight leakproof joint is provided, the ends of the clamp bearing on the upper 35 end of the outer casing.

If it is desired to utilize a limited volume of water for any desired purpose, a small pipe 33 is 40 threaded in the lower packing disc 25 and extends upwardly through a suitable opening provided in the upper disc, and is then led to any desired connection.

In Figs. 7 to 10 inclusive of the drawings I have 45 shown the upper end or top section of the device formed with a removable cover plate 34 so as to accommodate inner casings of various sizes, for example, if a four inch casing is used, a cover plate having a centrally disposed opening to fit this size casing is provided, the outer shell remaining the same, this will permit the outer shell or housing to be made up to suit a certain size outer casing, and it is then merely necessary to 50 select a cover plate having a centrally disposed opening of proper size to suit the inner casing.

55 The plates 34 are formed as clearly shown in Figs. 9 and 10 of the drawings being split on the center line 35 into two individual sections, the outer and inner rims being moulded to form inner and outer grooves 36 and 37 respectively 60 and these grooves are adapted to accommodate a suitable packing material 38, the outer rim 37 receiving the edge 39 of the outer shell, the inner rim snugly fitting the outer circumference of the inner casing, thus forming a tight water- 65 proof joint, these plates can be readily assembled with the shell and permit quantity production of the outer shells, and a plurality of different sizes of cover plates can be carried in stock.

From the foregoing description, it will be obvious that I have perfected a very simple, practical, and effective water shut-off for oil wells and the like.

What I claim is:

1. A shut-off for oil wells comprising inner and outer casings, a casing clamp clamped on the inner casing with its ends mounted on the outer casing, a cylindrical shell member mounted on the outer casing of the well and forming a closure 10 for the space between the inner and outer casings at the upper end thereof, laterally projecting chambers formed integral with the cylindrical member for accommodating the ends of the casing clamp, and means for rigidly clamping 15 the cylindrical member on said casing.

2. A shut-off for oil wells comprising a divided cylindrical member adapted to be clamped to the upper end of the outer casing and form a leak-proof closure between the inner and outer casing, a clamp on the inner casing opposed laterally extending chambers formed integral with said member for accommodating the ends of the clamp, and means for rigidly clamping said member in position.

20 3. An oil well structure comprising inner and outer casings, a clamp mounted on the inner casing and engaging the outer casing for suspending the inner casing thereon, means mounted on the outer casing for forming a leakproof closure between the inner and outer casings, and chambers in said closure means for accommodating the ends of the clamp.

30 4. An oil well shut-off structure comprising inner and outer casings, a clamp mounted on the inner casing and engaging the outer casing for suspending the inner casing thereon, a cylindrical shell adapted to be clamped to the outer casing of the well, and a removable cover plate engageable with said shell and forming a leak-proof closure between said outer casing and the inner casing of the well.

35 5. An oil well shut-off structure comprising inner and outer casings, a clamp secured on the inner casing and mounted on the outer casing, a pair of similar shell sections adapted to be clamped to the outer casing, and a sectional removable cover plate engageable with said shell sections and with the inner casing of the well to form a leakproof closure between the inner and outer casings.

40 6. An oil well shut-off structure comprising inner and outer casings, a clamp rigidly secured on the inner casing and supported on the outer casing, a cylindrical shell adapted to be clamped to the outer casing, and a detachable cover plate forming a closure between said shell and the inner casing, said plate being formed with packing grooves in the inner and outer edges thereof to form leakproof joints therewith.

45 7. An oil well structure comprising inner and outer casings, a clamp rigidly mounted on the inner casing and engaging the outer casing for suspending the inner casing thereon, and a cylindrical shell mounted on the outer casing with its upper end engaging the inner casing to form a leak proof closure between the inner and outer casings.

CHARLES A. BROWN.
